UNITED STATES PATENT OFFICE

CURT W. KLOSTERMANN, OF CHICAGO, ILLINOIS, ASSIGNOR TO MECHANICAL VENDING CORPORATION, OF CHICAGO, ILLINOIS, A CORPORATION OF DELAWARE

VENDING MACHINE

Application filed December 4, 1929. Serial No. 411,476.

This invention relates to vending machines and particularly to machines of the coin actuated type, wherein a coin or coins are employed for connecting the operating means to the discharge mechanism for ejecting articles of merchandise from the machine.

One object of the present invention is to provide a novel construction and arrangement wherein a plurality of coins of different 10 denomination or value are employed for connecting the operating means and the discharge mechanism.

Another object of the invention is to provide a novel coin controlled mechanism for 15 preventing clogging of the machine in the event that coins are deposited in the machine before the starting and completing of an article discharging operation.

Another object of the invention is to provide 20 means for preventing more than a predetermined number of coins of a particular denomination from entering the connecting means between operations of the discharge mechanism.

Another object of the invention is to provide 25 means adapted to be actuated by a coin deposited in the machine for preventing subsequent coins of like denomination from being conducted to the connecting means until 30 after the discharge mechanism has been actuated.

Another object of the invention is to provide 35 means adapted to be actuated by a coin deposited in the machine for moving said means from its normally inoperative position into operative position to deflect coins subsequently deposited in the machine away from the connecting means until after the discharge mechanism has been actuated, and 40 also to provide means actuated by the discharge mechanism for restoring the deflecting means to its normal position.

Another object of the invention is to provide 45 resiliently yielding means for releasably securing the coin actuated deflecting means in operative and inoperative positions.

Another object of the invention is to provide 50 a discharge mechanism having coin receiving means associated therewith adapted to be actuated by a plurality of coins of dif-

ferent denomination or value and means for preventing more than a predetermined number of coins of each denomination from being deposited in the receiving means between operations of the discharge mechanism.

A further object of the invention is to provide 55 a machine of the character described which is durable and practical, simple in construction, and efficient in its operation.

A still further object of the present invention is to improve machines of the character disclosed in sundry details hereinafter described and particularly pointed out in the appended claims.

One embodiment of the present invention is 60 shown for illustrative purposes in the accompanying drawings in which:

Fig. 1 is a vertical sectional view through a vending machine illustrating the application of the present invention thereto;

Fig. 2 is a fragmentary elevational view of 70 a portion of the mechanism illustrated in Fig. 1 and taken substantially as indicated by the line 2-2 thereof;

Fig. 3 is an enlarged elevational view of the 75 coin controlled connecting means and the coin actuated coin deflecting means associated therewith;

Fig. 4 is an enlarged elevational view of the 80 deflecting means and associated parts taken substantially as indicated by the line 4-4 of Fig. 3;

Fig. 5 is a fragmentary elevational view 85 having parts thereof broken away to illustrate more clearly the construction of the deflecting means, the view being taken substantially as indicated by the line 5-5 of Fig. 4;

Fig. 6 is a view similar to Fig. 3 showing 90 some of the parts in slightly changed positions;

Fig. 7 is a sectional elevation view taken substantially as indicated by the line 7-7 of Fig. 6;

Fig. 8 is an end view of the yielding mov- 95 able element employed for securing the deflecting means in operative and inoperative positions;

Fig. 9 is a side elevational view of the de- 100 vice shown in Fig. 8; and

Fig. 10 is an enlarged perspective view of one of the coin deflecting devices illustrating the relative position of tripping or actuating means associated therewith;

- 5 The illustrative embodiment of the invention shown in the drawings comprises a housing 10 having preferably a plurality of magazines 11 formed therein, one of which is shown in Figs. 1 and 3 of the drawings, 10 the respective magazines being adapted to contain a plurality of articles of merchandise, such for example, as packages of cigarettes indicated in Figs. 1, 3 and 6 of the drawings by the numeral 12.
- 15 The housing 10 in the present instance, is provided on its front vertical side with vertically disposed longitudinally extending sight openings 13 having transparent panels 14 such as glass or other suitable material mounted therein to enable the purchaser to observe the character of the articles of merchandise contained in the magazines.
- 20 The front portion of the machine, in the present instance, adjacent the lower end thereof, is provided with an aperture 15 through which access may be had to a pocket 16 into which the articles of merchandise are delivered when ejected from the magazines, and the housing is also provided, adjacent 25 one end of the aperture 15, with a coin pocket 17 into which coins or other tokens rejected by the machine may be deposited and from which they may be recovered by the purchaser.
- 25 For discharging articles from the magazine, a shaft 18 is rotatably mounted at its end portions in suitably positioned bearings carried by the housing of the machine and provided with discharge plates 19 rotatably 30 mounted on the shaft and spaced longitudinally thereof adjacent the lower ends of the respective magazines only one of said plates being shown in the present instance and indicated by the numeral 19. Formed on the periphery of the plates 19 are radially disposed annularly spaced fingers 20 adapted to traverse the lower portion of the magazine in a manner to engage the lowermost article therein and move the article transversely 35 with respect to the magazine as shown in Fig. 6 and deposit it into the chute 21 by which it is conducted to the pocket 16 where it may be removed through the aperture 15 by the purchaser.
- 40 For rotating the plates 19 and fingers 20 for discharging articles from the magazine, the shaft 18, adjacent one of its end portions, has secured thereto by any suitable means, a 45 manually operated hand lever 22 extending outwardly through a slot formed in the front portion of the housing and provided on its outer or free end with a knob 23 by which the purchaser may rotate the shaft 18 for operating the machine.

As previously stated, the present invention is of the coin actuated type, and in the present instance, the article discharging fingers 20 are adapted to be actuated by a plurality of coins of different denominations, for example, a dime and a nickel deposited in the article discharging mechanism.

Referring particularly to Figs. 1, 3, 6 and 7, it will be noted that one face of the plate 19 is provided with a plurality of radially disposed annularly spaced channels or coin receptacles 24 adapted to receive coins from coin conducting chutes 25 and 26, the chute 25, in the present instance, being adapted to receive nickels and conduct them to the channels of the discharge mechanism and the chute 26 being adapted to receive dimes for conducting them to the discharge mechanism. The plate 19 is also provided with annularly formed grooves 27 communicating, adjacent their end portions, with the channels 24.

Secured to the shaft 18, adjacent the channeled and grooved face of the plate 19 in a manner to close the open sides of the channels 24 when in operative position is an actuating member 28 of segmental form, and having a portion 29 formed thereon adapted to extend into the plane of the channels in a manner to support the lowermost coin such for example as a dime deposited in the channel as indicated at A in Figs. 1, 6 and 7 of the drawings. The member 28 is also provided with an arcuate rib 30 adapted to extend into the grooves 27 in a manner to engage a second coin such for example as a nickel deposited in the channel 24 as indicated at B in Figs. 1, 6 and 7 of the drawings.

It will be noted that when two coins are deposited in a channel or receptacle 24 in edge-wise alignment with respect to each other as indicated at A—B in Figs. 1, 6 and 7, the coins are held against displacement by the walls of the channel and the adjacent face of the actuating member 28, with the uppermost coin indicated at B in position to be engaged by the forward or adjacent end of the rib 30, and by forcing the outer or free end of the lever 22 downwardly by means of the knob 23, the shaft 18 and actuating member 28 secured thereto will be rotated and the forward end of the rib 30 will be brought into engagement with the adjacent edge of the coin B in a manner to cause the coin to impinge the opposite wall of the channel 24 in which it is mounted and rotate the plate 19 and fingers 20 carried thereby into engagement with the lowermost article in the magazine 11 for discharging the article therefrom and into the chute 21 and pocket 16. Secured to a rearwardly extending portion 31 of the lever 22 is one end of a spring 32, the opposite end of which is secured to a lug 33 mounted on the base or bottom portion 34 of the machine, for returning the operating le-

ver 22 and actuating member 28 to their normal or initial positions.

After an article discharging operation, the plate 19 will be retained in its changed position by suitable detent means 34a (Fig. 1) 5 cooperating with a cam plate 34b (Fig. 7), the said means being fully described in my copending application, filed December 2, 1929, Serial No. 411,035, and as the operating lever 22 and actuating member 28 are returned to their normal or initial positions by the action of the spring 32, it will be noted that the portion 29 will be moved from beneath the channel 24 in which the coins were 10 deposited to enable the last operation of the machine, thereby clearing the lower end of the channel and permitting the coins to drop by gravity therefrom into a suitable coin box positioned in the bottom of the machine and indicated by the reference character C.

Positioned adjacent the upper end portion of the housing 10, preferably on the front side thereof, are a plurality of slots adapted to receive coins such as dimes and nickels, respectively, employed for operating the mechanism shown in the present embodiment, and suitably positioned inside the housing and communicating with the respective slots are runways 35 and 36 open at their lower edge 15 portion as indicated at 37 in Fig. 1 adjacent the upper ends of the coin chutes 25 and 26 for depositing coins inserted in the slots into the respective chutes 25 and 26 by which the coins are conducted to the discharge mechanism, the runway 35, in the present instance, being adapted to receive nickels and communicating with the chute 25, and the runway 36 being adapted to receive dimes and communicating with the chute 26. It will be 20 noted by reference to Fig. 2 that the runways are inclined transversely at an angle to the perpendicular and provided in their lower or outer side portions with an elongated opening 38 through which coins or tokens of lesser diameter than those intended 25 for use in the particular runway are ejected onto an inclined plate 39 from which the coins or tokens are deposited into a transversely extending slide 40, the lower end portion 30 of which is adapted to communicate with a coin or token discharge chute 41 by which the rejected coins or tokens are conducted to the coin pocket 17 from which they may be repossessed by the customer.

For detecting or withdrawing coins or tokens of improper material from the machine, the respective chutes 25 and 26 are provided with magnets 42 which will hold the coins or tokens of such objectionable material sufficiently long to cause the coins or tokens to swing rearwardly through openings 43 formed in the rear edge of the respective chutes 25 and 26 and deposit the coins or tokens on the slide 40 by which they 45 are conducted to the chute 41 and thence to

the pocket 17 from which they may be recovered by the customer.

As above described, the present invention contemplates the use of coins of different denominations for actuating the discharge mechanism, and for preventing the operation of the machine by coins of like denomination, suitable means adapted to be actuated by the first coins of the respective denominations deposited in the machine are employed for deflecting coins of like denomination subsequently deposited away from the discharge mechanism, and in the present instance, this means comprises a frame 44 having a plurality of passages 45 and 46 extending vertically therethrough and adapted to communicate at their upper end portions with the lower ends of the chutes 25 and 26, respectively, for conducting coins deposited in the respective chutes to the lower end of 70 the frame and into the coin receptacles or channels 24 for actuating the discharge mechanism in the manner above described.

Pivottally mounted in the frame 44 and the ears or hangers 47 and 48 formed integral therewith are a plurality of aligned rock shafts 49 and 50 having their inner or adjacent end portions terminating within the passages 45 and 46, respectively, of the frame 44. Rigidly secured to the respective inner end portions of the shafts 49 and 50 are gates or deflectors 51 and 52, having coin actuated means such as fingers 53 and 54 associated with the respective gates or deflectors 51 and 52, the finger 53 being adapted normally to extend into the passage 45 in a manner to be engaged by a nickel as indicated by the character D in Fig. 3 of the drawings while its associated deflector 51 occupies a position to the rear of the passage as indicated also in 100 Fig. 3.

For retaining the deflector 51 and finger 53 in their respective normal positions as illustrated in Fig. 3 of the drawings, the ear or hanger 47 is provided with a boss 55 having a notch 56 formed therein adapted to receive a detent or tooth 57 formed on a collar 58 loosely mounted on the shaft 49, and having a slot 59 formed therein adapted to receive the ends of a pin 60 mounted in the shaft 49 110 in a manner to cause the collar to rotate or rock with the shaft 49 and at the same time permit longitudinal movement of the collar along the shaft to permit the withdrawal of the detent or tooth 57 from the notch 56 and move it into engagement with a notch 61 also formed on the boss 55.

For yieldingly holding the detent or tooth 57 in the respective notches, a relatively light spring 62 is positioned around the shaft 49 between the collar 58 and a head or nut 63 adjustably secured to the outer end of the shaft 49 in a manner to exert a suitable tension on the collar 58.

It will be observed from the foregoing de-

- scription that when a coin deposited in the chute 25 engages the trip or finger 53, the shaft 49 will be rotated in its bearings and the collar and tooth 56 moved outwardly 5 against the action of the spring 62, and the finger 53 will be moved to the position shown in Fig. 1 while the gate or deflector 51 will be moved into the passage 45 as shown in Fig. 1, and into a position to be engaged by coins 10 subsequently deposited in the chute 25 as indicated at E in Fig. 1, thereby causing such subsequent coins to be deflected away from the coin receptacle or discharge mechanism and into an inclined open chute or runway 64 15 (Fig. 1) by which the coins subsequently deposited are conducted to the chute or runway 41 and thence to the coin pocket 17 where they may be recovered by the customer.

Similar mechanism governs the course of 20 the coins from the chute 26 through the passage 46, the finger 54 being normally positioned in the passage in a manner to be engaged by a coin as, for example, a dime deposited therein from the chute 26 in which 25 case the dime would engage the finger 54 positioned normally in the passage 46 and move the finger and gate 52 to the position shown in Fig. 5 for deflecting dimes subsequently deposited in the machine away from 30 the coin receptacle and discharge mechanism in the manner described with reference to coins deposited in the passage 45.

The finger 54 and gate or deflector 52 are normally retained in their respective operative and inoperative positions in a manner similar to that described with reference to the finger 53 and deflector 51, the ear or hanger 48 being provided with a boss 65 having notches 66 and 67 formed therein adapted, in the various positions of the deflector 52, to receive a detent or tooth 68 formed on a collar 69 loosely mounted on the shaft 50, and provided with a slot 70 adapted to receive a pin 71 mounted in the shaft and cooperable 45 with the collar in a manner to cause the collar to rotate with the shaft and at the same time permit longitudinal movement of the collar relative thereto. The collar 69 and detent or tooth 68 is held yieldingly toward the boss 50 55 by means of a spring 72 operating between the collar and a head 73 adjustably secured to the shaft 50.

The passages 45 and 46 are connected, adjacent their lower ends as indicated at 74, 55 (Fig. 4) by a common passage for conducting the coins of respective denominations to the channels or coin receptacles 24 of the discharge mechanism.

For returning the deflectors 51 and 52 and 60 their actuating fingers 53 and 54, respectively, to their normal positions after the proper coins have been deposited in the coin receptacle of the discharge mechanism, each of the shafts 49 and 50 are provided with arms 65 75 and 76 adapted to be engaged by the fin-

gers 20 of the article discharge mechanism when the plate 19 and fingers 20 are rotated in a manner to discharge one of the packages or articles 12 from the magazine.

It will be observed from the foregoing description that when the fingers 53 and 54, and deflectors 51 and 52 are in their normal position, a nickel conducted to the frame 44 by the chute 25 will engage the finger 53 and in passing to the coin receptacle of the discharge mechanism will rotate the shaft 49 and move the deflector 51 into the passage 45 in a manner to be engaged by coins subsequently deposited in the chute 25 and return them to the purchaser, while the first dime deposited in the passage 46 by the chute 26 will engage the finger 54 and in its passage to the receptacle 24 will rotate the shaft 50 and move the deflector 52 into the passage 46 in a manner to be engaged by dimes subsequently deposited in the chute 26 and return them to the customer. The coins thus deposited in the channel or coin receptacles 24 of the discharge mechanism provide a driving connection between the actuating member 28 and plate 19 for rotating the plate in a manner to discharge an article of merchandise from the magazine 11, and in rotating the plate, one set of the fingers mounted thereon will engage the arms 75 and 76 in a manner to rotate the shafts 49 and 50 and restore the fingers 53 and 54 together with their associated gates or deflectors to normal or initial position.

Thus, it will be observed that but one coin of each denomination is permitted to enter a coin receptacle or channel 24 between operations of the coin discharge mechanism, thereby preventing the operation of the machine by two nickels, in which case the merchant would sustain a loss, or by two dimes, in which case the purchaser would be out the difference between the amount deposited and the price of the article purchased.

It will be observed from the foregoing description that the present invention provides a novel coin actuated vending machine adapted to be operated through the medium of a plurality of coins of different denominations, and wherein any loss either to the purchaser or merchant is eliminated. It will be understood that machines of the character described may be designed in a manner to be operated by more than two coins, in which case as many additional coin passages and similar coin actuated deflecting means may be added as desired.

Obviously, the present invention is not limited to the precise construction and arrangement shown and described as the same may be variously modified. Moreover, all the features of the invention need not be used conjointly as the same may be used to advantage in variously different combinations and sub-combinations.

Having thus described my invention, I claim:

1. In a vending machine, the combination with manually operated coin controlled ejecting means for discharging articles therefrom including a coin receptacle and a chute for conducting coins to said receptacle, of deflecting means operatively related to said chute and having means associated therewith adapted to be engaged by the first coin deposited in said chute for actuating said deflecting means in a manner to cause coins subsequently deposited in said chute to be deflected away from said receptacle, and means adapted to be engaged by said ejecting means for restoring said deflecting means to normal position.
2. In a vending machine, the combination with manually operated coin controlled ejecting means for discharging articles therefrom including a coin receptacle and a chute for conducting coins to said receptacle, of a deflector pivotally mounted adjacent said chute, means operatively related to said deflector and adapted to be engaged by a coin deposited in said chute in a manner to move said deflector into the chute for deflecting coins subsequently deposited therein away from said receptacle, and means operatively related to said deflector and adapted to be engaged by said ejecting means for restoring the deflector to its initial position.
3. In a vending machine, the combination with manually operated coin controlled ejecting means for discharging articles therefrom including a coin receptacle and a chute for conducting coins to said receptacle, of a deflector pivotally mounted adjacent said chute, means operatively related to said deflector and adapted to be engaged by a coin deposited in said chute in a manner to move said deflector into the chute for deflecting coins subsequently deposited therein away from said receptacle, means operatively related to said deflector and adapted to be engaged by said ejecting means for restoring the deflector to its initial position, and yielding means for releasably securing said deflecting means in operative and inoperative positions.
4. In a vending machine, the combination with coin controlled ejecting means for discharging articles therefrom including a coin receptacle adapted to receive a plurality of coins, means for actuating said ejecting means and a plurality of chutes for conducting coins of different denominations to said receptacle, of pivotally mounted means positioned in each of said chutes and adapted to be actuated by the first coin deposited therein in a manner to deflect coins subsequently deposited in the respective chutes away from said receptacle until after said ejecting means has been actuated, means for restoring said deflecting means to inoperative position, and yielding spring actuated means for releasably securing said deflecting means in operative and inoperative positions.
5. In a vending machine, the combination with coin controlled ejecting means for discharging articles therefrom including a coin receptacle adapted to receive a plurality of coins, means for actuating said ejecting means and a plurality of chutes for conducting coins of different denominations to said receptacle, of pivotally mounted coin actuated means positioned in each of said chutes for deflecting a second coin deposited in the respective chutes away from said receptacle until after said ejecting means has been actuated, and means operatively related to said ejecting means for restoring said deflecting means to inoperative position.
6. In a vending machine, the combination with manually operated coin controlled ejecting means for discharging articles therefrom including a coin receptacle and a plurality of chutes for conducting coins of different denominations to said receptacle, of deflecting means operatively related to each of said chutes and having means associated therewith adapted to be engaged by the first coin deposited in the respective chutes for actuating said deflecting means in a manner to cause coins subsequently deposited in the respective chutes to be deflected away from said receptacle, and means adapted to be engaged by said ejecting means for restoring said deflecting means to normal position.
7. In a vending machine, the combination with manually operated coin controlled ejecting means adapted to be actuated by a plurality of coins of different denominations and having a coin receptacle associated therewith, of a plurality of chutes for conducting coins to said receptacle, deflecting means for preventing more than one coin of like denomination from entering said receptacle between operations of said ejecting means, means for restoring said deflecting means to inoperative position, and means for releasably securing said deflecting means in operative and inoperative positions.
- In witness whereof, I hereunto subscribe my name this 27th day of November, A. D. 1929.
- CURT W. KLOSTERMANN.
